PROCESS AND MEANS FOR WINDING
NATURAL AND SYNTHETIC YARNSAlbert Nau-Touron, Paris, France, assignor to
Isaac Frenkel, Paris, France

Application May 3, 1950, Serial No. 159,705

Claims priority, application France May 4, 1949

10 Claims. (Cl. 57—67)

1

The present invention relates to a process and means for spinning and twisting natural and synthetic yarns. These process and means which may be broadly used and notably in spinning and twisting frames are also applicable to cabling or a similar operation.

The main object of the invention is to provide a process for passing the yarn for rotary spinning and twisting members wherein the yarn is caused to pass, before it winds on the rotary spooling or similar member, in such a manner that it is applied on the yarn or thread already wound on said member in the zone on which the winding occurs and then on said member or on the yarn or thread already wound on the latter in the zone diametrically opposed to that on which said winding occurs, said last application being effected on a diameter less than the diameter on which the first application is effected. Moreover, the yarn tension is regularized by effecting these successive yarn applications on the bobbin in planes positioned below that in which the yarn is wound on the bobbin or similar member.

According to a preferred embodiment of the invention utilizing a spinning flyer of known type, the latter has perforations or the like so arranged that the yarn, after frictionally engaging the outer surface of the spinning flyer and before it winds on the rotary spooling member, is caused to pass on the yarn already wound, with a certain pressure along a convex path, then through the wall of the spinning flyer and back on the yarn already wound on the diametrically opposite side of the rotary member, again with a certain pressure and according to a convex path, subsequently anew through the wall of the spinning flyer and finally back again to wind itself on the spooling member.

This invention is not only applicable to devices of the so-called spinning flyer type but also to similar arrangements of the types now in use and notably:

- (a) To flyers which in this case will be provided with perforated end blades for passing the yarn as disclosed above;
- (b) To rotary ring travellers;
- (c) To fixed ring travellers and other similar members.

The perforations for the passage of the yarn in the spinning flyer or the like may be made to open sidewise through a groove or slot conveniently inclined for introducing or extracting the yarn, these perforations being located in the same plane or in different planes suitably spaced apart.

2

The rotary spooling member, such as a spindle or like member effecting on the latter or on its bobbin the desired spooling action, may consist of a driving member while the spinning flyer or similar device effecting the twisting and the relative drag in angular velocity for the spooling and exerting the tension on the yarn are merely braked.

Reversely the spinning flyer or similar member adapted to twist the yarn may be a driving member while the spooling member, for instance a spindle or similar member, which effects the yarn spooling and tensioning action is merely braked.

According to a further embodiment the braking of the spooling member may be obtained in suitable conditions, i. e. in accordance with the variable spooling diameter, by the action of the yarn passing on the portion already wound.

Similarly, the spinning flyer may be fixed or mounted freely on a ring member rotating freely in relation to the vertical alternating motion device of the spinning or twisting frame and in this last case the spinning flyer is connected to the rotary ring by means of at least three parts in sliding engagement with the ring.

With the novel process and means for passing the yarn according to the invention the driving of the rotary members is materially facilitated and more flexible, the yarn is subjected to a substantially uniform tension with a constant braking in spite of the varying spooling diameter, the risk of breaking the produced yarn is less, piecings are made easier and spindle velocities are greater and their production is increased correspondingly.

The invention extends also to other specific features which will appear from time to time in the following description in connection with the affixed drawings given solely by way of example.

In the drawings:

Fig. 1 is an elevational view of a first embodiment comprising a driven bobbin;

Fig. 2 is a plane view thereof.

Fig. 3 is an elevational view of another embodiment comprising a driven bobbin;

Fig. 4 is a plane view thereof.

Fig. 5 is a modified embodiment of the spinning flyer seen from the outside.

Figs. 6, 7 are perspective views from front and back respectively of a spinning flyer according to the embodiment of Figs. 3, 4.

Figs. 8, 9 are perspective views of the front and back portions of a spinning flyer according

to the embodiment of Figs. 3 and 4 adapted for operation in both directions of rotation.

Fig. 10 is an elevational view of an embodiment comprising a driven bobbin wherein the spinning flyer is fast with rotary ring member of the vertical alternating motion device.

Fig. 11 is an elevational and sectional axial view of a spinning flyer movable in relation to a fixed ring of the vertical alternating motion device.

Fig. 12 is an elevational and sectional axial view of a spinning flyer movable in relation to a fixed ring member of the vertical alternating motion device.

Figs. 13, 14 illustrate various embodiments of spinning flyer devices.

Figs. 15, 16 are elevational and plane views respectively of a flyer device.

Fig. 17 shows a modification in the embodiment illustrated in Fig. 11.

Referring to Figs. 1 and 2 the spindle 1 has removably fitted thereon according to the conventional method a bobbin 2 of the type having successively superposed tapered layers. The spindle 1 may rotate for instance in the direction of the arrow 3. As indicated above the direction of rotation may be the reverse as well. The yarn 4 is wound on bobbin 2 by means of a spinning flyer 6, said spinning flyer or the spindle being connected to the copping motion in the conventional manner.

During the rotational movement of spindle 1, the path of linear displacement of yarn from balloon 4 where it is submitted to a tension t_1 toward bobbin 2 is as follows:

(1) Through peripheral perforation 5 of spinning flyer 6;

(2) Through perforation 7 of said spinning flyer, whereby a peripheral frictional engagement is produced at an angle α which induces a smoothing effect, while the yarn which emerges from said perforation 7 is submitted to a tension t_2 greater than t_1 ;

(3) Across spinning flyer 6 into perforation 8, the yarn which passes between perforations 7 and 8 bearing on a layer of the yarn already wound on the bobbin 2 according to an arc of a circle A centered on the spindle axis and having a diameter D_1 ;

(4) Through perforation 9 of said spinning flyer, whereby a peripheral frictional engagement is produced at an angle β , while the yarn which emerges from said perforation 9 is submitted to a tension t_3 greater than t_2 ;

(5) Again across spinning flyer 6 into perforation 10, the yarn which passes between perforations 9 and 10 bearing on a layer of the yarn already wound on the bobbin 2 according to an arc of a circle B centered on the spindle axis and having a diameter D_2 less than D_1 , said arc B being substantially diametrically opposed to the arc A with respect to the spindle axis;

(6) Through perforation 11 of said spinning flyer, whereby a peripheral frictional engagement is produced at an angle ρ , while the yarn which emerges from said perforation 11 is submitted to a tension t_4 greater than t_3 and finally wound on bobbin 2 at a point C, winding point, located on the same side of bobbin 2 as the first arc of a circle.

Said various perforations or apertures 5, 7, 8, 9, 10 and 11 open laterally for allowing the yarn to be placed in position or removed. The distribution of said perforations on the spinning flyer is so effected that the parts of the strand extend-

ing into said flyer would follow a path forming an angle less than 180° between the inlet and outlet perforations if said strand was applied against the bobbin. In the example shown in the various figures, such a result is obtained by respectively locating the successive inlet perforations, such as 7, 9 and 11, and the successive outlet perforations, such as 8 and 10, in substantial diametrical opposition, the shortest distance existing between the corresponding diametral planes of location being less than the diameter of the bobbin. Preferably the inlet perforations for the parts of the strand passing in the winding zone have a common lateral opening, such as perforations 7 and 11 (Fig. 1).

Thus, perforations 7, 8 of spinning flyer 6 are included in a horizontal plane P1 located below the horizontal plane P2 containing the next perforations 9, 10 and 11 of the yarn path. The horizontal plane P1 containing the yarn strand directed to the inside of spinning flyer 6 from perforation 7 to perforation 8 is therefore located at a level below plane P2 which contains both strands from perforation 9 to perforation 10 and from perforation 10 to perforation 11.

Owing to the bobbin formation firstly considered, using superposed tapered layers, it automatically follows that the diameter D_1 of a layer in relation to the lower plane P1 has a numerical value higher than the diameter D_2 of a layer in relation to the upper plane P2.

Let

Ω = momentary speed of rotation of spindle 1 and bobbin 2;

L = momentary linear output of the feeding cylinders;

ω_1 = momentary speed of rotation of spinning flyer 6 corresponding to diameter D_1 (plane P1);

ω_2 = momentary speed of rotation of spinning flyer 6 corresponding to diameter D_2 (plane P2).

We know that the angular deceleration of the spinning flyer with respect to the bobbin is equal to the ratio existing between the linear output L of the feeding cylinders and the linear winding speed at the level where said winding occurs, whereby:

$$\omega_1 = \Omega - \frac{L}{\pi D_1}$$

$$\omega_2 = \Omega - \frac{L}{\pi D_2}$$

Now, for the momentary spooling on the real momentary spooling diameter D_2 corresponding to plane P2 containing perforations 9, 10 and 11 the real momentary spooling speed ω_2 is lower than the momentary speed ω_1 of the impulse which assists rotation, corresponding to the rotation-assisting momentary diameter D_1 corresponding to plane P1 containing the other perforations 7 and 8.

Thus, through the medium of the strand subjected to a tension t_3 from perforation 7 through the inside of spinning flyer 6 to perforation 8 the rotation of the spinning flyer will be materially assisted as well as, of course, the rotation of the rotation members fast therewith.

In short, this strand will notably assist the tangent strand from perforation 11 to the momentary point at which the yarn is being wound on the bobbin in the work assigned to this tangent strand consisting in rotationally driving

spinning flyer 6 together with the freely rotating members which form a single body therewith.

This contribution in the rotational drive results from the difference between momentary speeds ω_1 and ω_2 .

It is a function, on the one hand, of the distance H between planes $P1$ and $P2$, on the other hand, of the angle θ at which the spooling layer is tapered.

Referring to this taper it should be noted that:

(1) In the hitherto considered bobbin formation by superposed tapered layers and at the beginning of this formation the conical shape of the tube itself, although its angle is much smaller than θ , will be operative but with less importance;

When it is desired to obtain the same efficiency as that of the layers which form the body of the bobbin, a tapered-base tube having an angle θ and of conventional commercial type may be used.

(2) In the bobbin formation by superposed cylindrical layers a slight taper provided on the bobbin combined with a distance H' greater than H gives a contribution in the rotation of spinning flyer 6 or similar member.

The yarn strand which passes inside spinning flyer 6 from perforation 9 to perforation 10 and is subjected to a tension t_3 will cooperate with the previous strand in assisting the rotational drive of spinning flyer 6 by the tangent strand.

Thus, yarn breaking factors are further reduced accordingly.

Besides, the yarn tension is very substantially regularized in spite of the variation in the momentary spooling diameter of the bobbin tapered layer while a constant braking action is used.

Finally, this novel passage of the yarn produces designedly a pair of yarn triangles within the spinning flyer 6. As a consequence thereof and owing to the convenient angular arrangement of perforations 7, 8, 9, 10 and 11 the composition of the resultants of tensions t_2 , t_3 and t_4 acting in operation upon their relative strands and directed toward the axis of symmetry xy are much improved. The causes of vibration of spindle 1 and bobbin 2, and other revolving members are materially reduced.

With this double triangulation the application of yarn from perforation 7 to perforation 8 occurs on the zone which coincides with the winding of this yarn on the bobbin but not on the opposite zone.

In the foregoing perforations 7, 8 only were contained in the lower plane $P1$, which is in accordance with Figs. 1 and 2.

In Figs. 3 and 4 the lower plane $P1$ contains also perforations 9a and 10a which follow perforations 7a and 8a in the path of yarn 4a.

In order to isolate from each other the planes $P1$, $P2$ in which the yarn is passed a rib 12 may be provided on the spinning flyer 6b as shown in Fig. 5. Of course, this rib is intersected by the yarn passage slots shown in Figs. 1 and 3. These slots are oblique to the axis xy , communicate with the perforations and facilitate the passage of the yarn. The perforations are splayed out and polished in order to avoid dragging the yarn along its linear travel in relation to the spinning flyer.

The above-described yarn passage is applicable in the same manner to any type of spinning flyer utilisation and whether rotation is clockwise or anti-clockwise. It applies also to ordinary flyers of suspended or reversed flyer frames as well as to bowls, bells or any other

similar member providing a combined twisting and spooling action.

Figs. 6 and 7 are perspective views illustrating a spinning flyer comprising the perforation arrangement of Figs. 3 and 4 and adapted to operate in the direction of the arrow 3a only. The front central portion includes a pair of yarn passages 13, 14 formed in the spinning flyer body for connecting perforations 7a and 10a, and perforations 10a and 11a, respectively.

Figs. 8 and 9 illustrate in perspective view a spinning flyer of a type similar to that shown in Figs. 6 and 7 but adapted to operate in the direction of the arrow 3d. The front central portion is provided with four perforations 1c, 10c, 11c and 11d connected by pairs through three yarn passages 13c, 14c and 14d. A further perforation 5d is provided in the left side portion of the spinning flyer. Considering a rotation in the direction of the arrow 3c, the yarn moves along path 5c, 1c, 8c, 9c, 10c and 11c while in the reverse direction, i. e., that of the arrow 3d, it moves along path 5d, 10c, 9c, 8c, 7c and 11d.

Fig. 10 illustrates another embodiment wherein a rod 21 is fixed to the frame of a spinning device 22 through arms 23. A ring member 24 mounted on ball bearings or similar parts may rotate freely in relation to rod 21. This ring member 24 carries a spinning flyer 6e. Rotation of annular member 24 and therefore spinning flyer 6e is effected by means of a rope or similar device 26. Spindle 25 rotates and is rocked on its pivot rod 30 fixed to plate 31, the latter being subjected to a vertical reciprocating motion indicated by the arrows 32. The yarn spooling spindle 25 has a groove 33 and a cylindrical portion or drum 34. A braking element 35 in frictional engagement with groove 33 has one end fixed and the other end attached to a drag-weight 36 acting as braking means. The part 37 of spindle 25 guides the plate 31.

The yarn 4e fed from the feeding cylinders 39 is passed through a yarn-guide 40 and an eye 41 either of the fixed or vertically adjustable type.

The eye 41 may be replaced with a pair of guiding threads 42 (Figs. 13 and 14). If desired ring member 41 and guiding threads 42 may be dispensed with.

Ring 24 and its spinning flyer 6e may be designed to ensure the passage of the bobbin and a brake may be provided for stopping ring carrying the spinning flyer during the operation of the spinning-frame.

A drum 34 is used for winding up a few turns of the yarn so as to save time in the lifting operation and eliminate the re-adjusting operation.

Bobbins may be formed either with parallel layers or with tapered layers.

The yarn from the yarn-guide 40 is passed through ring 41 or between threads 42 and then into one of the peripheral perforations 5e of spinning flyer 6e. This yarn will thus rub the outer surface of the spinning flyer, then pass through perforation 7e thereof and finally wind itself on the spindle according to the arrangement described in connection with Figs. 1-4.

Referring now to Fig. 11, the arrangement shown comprises a spinning flyer 6f formed in the same manner, having its perforations 5f, 7f, 8f, 9f, 10f and 11f disposed in the same relationship and fast with a ring member 15 by means of screw or any other suitable connecting device. This ring 15 has the minimum volume and weight and is preferably made of light- or ultra-light

metal or of plastics having heavy-duty characteristics, such as nylon or equivalent material.

At least three connecting members 16, fast with the ring member 15, are spaced at suitable angular intervals which may be regular or irregular. These connecting members 16, of tempered and polished steel or any other hard and smooth material, plastics or else, may have a laid-c shape as shown in the drawing.

The spinning flyer 6f may be integral with ring 15; in this case, members 16 are carried by this assembly.

Owing to the provision of these connecting members 16, ring 15 may move circularly and freely, with the minimum frictional resistance, in relation to a ring 17 of tempered and polished steel or any other suitable hard and smooth material, either plastic or not. This ring 17 may have a T-section as illustrated or any other section adapted to that of members 16 and to permit their free movements.

Ring 17 is fixed to the rotating ring 18 through any suitable and conventional means, for instance by crimping.

A dynamic balancing operation is carried out beforehand on ring 15 provided with its connecting members 16.

With the displacement of spinning flyer 6f in relation to ring 17, which is thus made possible, a great flexibility of operation is imparted to the rotating assembly; on the other hand, shocks are absorbed and the yarn is therefore protected during its manufacture. As a rule, this relative displacement is advantageous in that during full-speed operation the intervals and angular displacements of spinning flyer 6f are very low in relation to this ring 17 fast with the rotating ring 18, the latter being braked as before.

The assembly 6f-15 is yieldingly connected with ring 17 through the medium of the connecting members 16 owing to the components of the tensions acting upon the yarn strands outside spinning flyer 6f and, if necessary, to the effect of centrifugal forces acting upon a very slight and variable want of balance purposely provided, if desired, either on spinning flyer 6f or on ring 15.

The initial starting of the rotating assembly is very easily effected. In fact, as spinning flyer 6f is urged directly by the spindle and also by the yarn, the inertia of both ring 17 and this rotating assembly is progressively reduced to zero owing to the static and dynamic components cited above. Thus, the angular displacement of 6f in relation to 17 will be reduced with the same progressiveness until the above-mentioned full-speed rating is reached in a very short time. The object of this possibility of providing a flexible relative displacement of the parts concerned is to facilitate the piecing operation.

The circular movement of assembly 6f-15 in relation to ring 17 may be ensured by means of ball bearings or the like instead of connecting members 16, as illustrated in Fig. 17. The spinning flyer 6f is screwed on a ring 15a, balls 13a or like elements being located between said ring member 15a and a ring 17a fixed to the rotary ring 18.

In Fig. 12 a third embodiment is shown wherein in the spinning flyer 6g is displaceable circularly on a ring 17g fixed to the vertical reciprocating motion plate 19 of the frame.

In full-speed conditions the effect of speed together with the impulse-assisting action described above in connection with the spinning flyer fixed to the rotating ring, the rotary driving of spin-

ning flyer 6g is much facilitated while the yarn tension is regularized independently of the variations in winding or spooling diameter of the bobbin.

The same occurs when the spindle is started, owing to this same impulse driving action exerted on spinning flyer 6g; thus, both frame-starting and piecing operations are materially facilitated.

In the embodiment of Figs. 11, 12 and 17 the yarn is passed, as in the examples disclosed above, through perforations provided in the spinning flyer, not through the connecting members 16 or 16g.

The three last embodiments of the present invention may be also used with a spinning flyer of the type disclosed in the U. S. Patent No. 2,218,620, filed July 6, 1939, with the yarn passage system in accordance therewith.

Furthermore, this system may be also used with a constant or variable height of the balloon strand during the formation of the bobbin.

The embodiment shown in Fig. 13 differs from that of Fig. 10 only in that the spindle used is driven instead of being driven while the spinning flyer is of the driven type.

An arrangement which is the reverse of that shown in Figs. 10 and 13 may be used for the spinning flyer. This reversed arrangement is illustrated in Fig. 14 and comprises a reversed spinning flyer 6h. The passage of the yarn is therefore reversed as the yarn is passed through the bores of ring 24b and spinning flyer 6h with all the required clearance and then to the outside through perforation 7h and subsequently through the selected peripheral perforation 5h. With this arrangement it is possible to reduce the bores of ring 24b and spinning flyer 6h, whereby greater speeds and certain constructional facilities may be obtained.

Figs. 15 and 16 illustrate an improved flyer constructed in accordance with the invention in view of obtaining the novel passage of yarn which is a feature thereof. The yarn 41, after being partially wound on the flyer arm 50, is passed through a perforation 51 provided in a blade 52, then in holes 7k of blade 52, 8k and 9k of one blade 54 which terminates the other arm of the flyer and finally back to perforations 10k and 11k of blade 52. These perforations 7k to 11k correspond in principle to the positions of perforations 7-11 of the two-first embodiments described above and this improved flyer, which may be also of the reversed type, offers the same advantages as those indicated above.

It is obvious that the embodiments described and illustrated are given only by way of examples and not in a limiting sense. Thus any modifications which do not alter in any way the main features disclosed above or the desired result are to be considered as included in the scope of the present invention.

What I claim is:

1. A process for winding yarns supplied by delivering devices on rotary winding members, more particularly for spinning, twisting and cabling frames, comprising, in succession, the steps of bearing the strand of yarn to be wound on a layer of yarn already wound on the winding member according to an arc of a circle centered on the axis of said member while said strand of yarn is subjected to a tension greater than that generated by the delivering devices, of increasing the tension applied to said strand of yarn, of bearing the strand of yarn under the thus increased tension on a second layer of yarn

already wound on the winding member according to a second arc of a circle centered on said axis and substantially diametrically opposed to the first arc with respect to said axis, of increasing anew the tension applied to said strand of yarn, and finally of winding the strand of yarn under the thus anew increased tension on the winding member at a point located on the same side of said winding member as the first arc of a circle.

2. A process, according to claim 1, wherein the second arc of a circle and the winding point are located at the same level while the first arc of a circle is located at a lower level with respect to the axis of the winding member.

3. A process, according to claim 1, wherein both arcs of a circle are located at the same level while the winding point is located at a higher level with respect to the axis of the winding member.

4. In a textile machine more particularly for spinning and twisting natural and artificial textile yarns and for cabling or similar operation, of the type comprising a rotary spindle carrying a filling bobbin and a rotating ring coaxial therewith and rotating in the same direction while subjected to a braking action of constant value, said rotating ring and said rotary spindle being both subjected to relative axial displacement for distributing the yarn on said filling bobbin; the improvement which comprises a spinning flyer rotatably mounted on said rotating ring and formed with six apertures spaced from one another in the direction of rotation of said spindle for passing and guiding the yarn, the first aperture being used for passing outwards the yarn received from the delivering members of the machine, the second aperture being formed at an angle from the first aperture which is a function of the ratio to be obtained between the delivering and winding tensions of the yarn and being used for passing the yarn coming from said first aperture and which frictionally engages the outer surface of said spinning flyer, the third aperture being formed at an angle less than 180° from either said first and second apertures and being used for passing the yarn coming from said second aperture and which bears on a layer of yarn already wound on the filling bobbin according to an arc of a circle centered on the axis of the spindle, the fourth aperture being formed at a distance from the third aperture which is less than the diameter of the spindle and being used for passing the yarn coming from said third aperture and which frictionally engages the outer surface of the spinning flyer between said third and fourth apertures, the fifth aperture being formed at an angle less than 180° from said first and fourth apertures and being used for passing the yarn coming from said fourth aperture and which bears on a layer of yarn already wound on the filling bobbin according to a second arc of a circle centered on the spindle axis, said second arc being substantially diametrically opposed to the first one with respect to the axis of the spindle while the radius of said second arc is less than that of the first arc, and the sixth aperture being formed at a distance from the fifth aperture which is less than the diameter of the spindle, said sixth aperture being used for passing the yarn coming from said fifth aperture and which frictionally engages the outer surface of said spinning flyer between said fifth and sixth apertures, said yarn being finally wound on the bobbin at a point located on the same side of the filling bobbin as the first arc of a circle.

5. In a textile machine more particularly for spinning and twisting natural and artificial textile yarns and for cabling or similar operation, of the type comprising a rotary spindle carrying a filling bobbin and a rotating ring coaxial therewith and rotating in the same direction while subjected to a braking action of constant value, said rotating ring and said rotary spindle being both subjected to relative axial displacement for distributing the yarn on said filling bobbin; the improvement which comprises a spinning flyer fixedly mounted on said rotating ring and formed with six apertures spaced from one another in the direction of rotation of said spindle for passing and guiding the yarn, the first aperture being used for passing outwards the yarn received from the delivering members of the machine, the second aperture being formed at an angle from the first aperture which is a function of the ratio to be obtained between the delivering and winding tensions of the yarn and being used for passing the yarn coming from said first aperture and which frictionally engages the outer surface of said spinning flyer, the third aperture being formed at an angle less than 180° from either said first and second apertures and being used for passing the yarn coming from said second aperture and which bears on a layer of yarn already wound on the filling bobbin according to an arc of a circle centered on the axis of the spindle, the fourth aperture being formed at a distance from the third aperture which is less than the diameter of the spindle and being used for passing the yarn coming from said third aperture and which frictionally engages the outer surface of the spinning flyer between said third and fourth apertures, the fifth aperture being formed at an angle less than 180° from said first and fourth apertures and being used for passing the yarn coming from said fourth aperture and which bears on a layer of yarn already wound on the filling bobbin according to a second arc of a circle centered on the spindle axis, said second arc being substantially diametrically opposed to the first one with respect to the axis of the spindle while the radius of said second arc is less than that of the first arc, and the sixth aperture being formed at a distance from the fifth aperture which is less than the diameter of the spindle, said sixth aperture being used for passing the yarn coming from said fifth aperture and which frictionally engages the outer surface of said spinning flyer between said fifth and sixth apertures, said yarn being finally wound on the bobbin at a point located on the same side of the filling bobbin as the first arc of a circle.

6. In a textile machine more particularly for spinning and twisting natural and artificial textile yarns and for cabling or similar operation, of the type comprising a rotary spindle carrying a filling bobbin and a fixed ring coaxial therewith, said fixed ring and said rotary spindle being both subjected to relative axial displacement for distributing the yarn on said filling bobbin; the improvement which comprises a spinning flyer rotatably mounted on said fixed ring and formed with six apertures spaced from one another in the direction of rotation of said spindle for passing and guiding the yarn, the first aperture being used for passing outwards the yarn received from the delivering members of the machine, the second aperture being formed at an angle from the first aperture which is a function of the ratio to be obtained between the delivering and winding tensions of the yarn and being used for passing the yarn coming from said first aperture and which frictionally engages the outer surface of said spinning flyer between said first and second apertures, the third aperture being formed at an angle less than 180° from either said first and second apertures and being used for passing the yarn coming from said second aperture and which bears on a layer of yarn already wound on the filling bobbin according to a second arc of a circle centered on the spindle axis, said second arc being substantially diametrically opposed to the first one with respect to the axis of the spindle while the radius of said second arc is less than that of the first arc, and the fourth aperture being formed at a distance from the third aperture which is less than the diameter of the spindle, said fourth aperture being used for passing the yarn coming from said third aperture and which frictionally engages the outer surface of the spinning flyer between said third and fourth apertures, the fifth aperture being formed at an angle less than 180° from said first and fourth apertures and being used for passing the yarn coming from said fourth aperture and which bears on a layer of yarn already wound on the filling bobbin according to a first arc of a circle centered on the axis of the spindle, said first arc being substantially diametrically opposed to the second one with respect to the axis of the spindle while the radius of said first arc is less than that of the second arc, and the sixth aperture being formed at a distance from the fifth aperture which is less than the diameter of the spindle, said sixth aperture being used for passing the yarn coming from said fifth aperture and which frictionally engages the outer surface of said spinning flyer between said fifth and sixth apertures, said yarn being finally wound on the bobbin at a point located on the same side of the filling bobbin as the second arc of a circle.

ture and which frictionally engages the outer surface of said spinning flyer, the third aperture being formed at an angle less than 180° from either said first and second apertures and being used for passing the yarn coming from said second aperture and which bears on a layer of yarn already wound on the filling bobbin according to an arc of a circle centered on the axis of the spindle, the fourth aperture being formed at a distance from the third aperture which is less than the diameter of the spindle and being used for passing the yarn coming from said third aperture and which frictionally engages the outer surface of the spinning flyer between said third and fourth apertures, the fifth aperture being formed at an angle less than 180° from said first and fourth apertures and being used for passing the yarn coming from said fourth aperture and which bears on a layer of yarn already wound on the filling bobbin according to a second arc of a circle centered on the spindle axis, said second arc being substantially diametrically opposed to the first one with respect to the axis of the spindle while the radius of said second arc is less than that of the first arc, and the sixth aperture being formed at a distance from the fifth aperture which is less than the diameter of the spindle, said sixth aperture being used for passing the yarn coming from said fifth aperture and which frictionally engages the outer surface of said spinning flyer between said fifth and sixth apertures, said yarn being finally wound on the bobbin at a point located on the same side of the filling bobbin as the first arc of a circle.

7. A spinning flyer for textile machines more particularly for spinning, twisting, cabling or similar machines, of the type having a rotatable spindle equipped with a filling bobbin, said spinning flyer having six yarn passing and guiding apertures which are spaced from one another in the direction of rotation of the spindle, the second aperture being formed at an angle from the first aperture which is a function of the ratio to be obtained between the delivering and wind-

ing tensions of the yarn, the third aperture being formed at an angle less than 180° from either said first and second apertures, the fourth aperture being formed at a distance from the third aperture which is less than the diameter of the spindle, the fifth aperture being formed at an angle less than 180° from said first and fourth apertures, and the sixth aperture being formed at a distance from the fifth aperture which is less than the diameter of the spindle.

8. A spinning flyer, according to claim 7, wherein the first, fifth and sixth apertures are located substantially at the same level while the second, third and fourth apertures are located at a lower level.

9. A spinning flyer, according to claim 7, wherein the first, second, third, fourth and fifth apertures are located substantially at the same level while the sixth aperture is located at a higher level.

10. A spinning flyer, according to claim 7, further formed with a seventh aperture diametrically opposed to the first aperture and an eighth aperture located symmetrically to the sixth aperture in relation to the diametral plane passing in the middle of the interval existing between the second and fifth apertures, whereby the distribution of the yarn is effected in reverse directions when successively utilizing, on the one hand, the first, second, third, fourth, fifth and sixth apertures and, on the other hand, the seventh, fifth, fourth, third, second and eighth apertures.

ALBERT NAU-TOURON.
